UNITED STATES PATENT OFFICE.

GEORGE P. KINGSBURY, OF BROOKLYN, NEW YORK, ASSIGNOR TO MERGENTHALER LINOTYPE COMPANY, A CORPORATION OF NEW YORK.

TYPOGRAPHICAL CASTING-MACHINE.

1,265,343.

Specification of Letters Patent.

Patented May 7, 1918.

Application filed July 28, 1916. Serial No. 111,765.

To all whom it may concern:

Be it known that I, GEORGE P. KINGSBURY, a citizen of the United States, residing at Brooklyn, in the county of Kings and State 5 of New York, have invented certain new and useful Improvements in Typographical Casting-Machines, of which the following is a specification, reference being had therein to the accompanying drawing.

10 My invention relates to typographical machines, such as linotype machines of the general organization represented in U. S. Letters Patent to O. Mergenthaler, No. 436532, wherein a type bar or slug is cast in a slot-15 ted mold against an assembled line of matrices presented momentarily thereto and confined between a pair of clamping jaws, and wherein the slug after casting is removed from the mold by an ejector which advances 20 to the rear and pushes it forwardly between a pair of trimming knives into a receiving galley at the front of the machine.

In practice, it is frequently necessary to produce the type bars or slugs of different 25 lengths to accord with the width or measure of the body or column to be printed, and this practice necessarily involves the use of molds of appropriate length. It is also essential in most instances that both the ejector 30 and the line clamping jaws be adjusted to correspond to the length of the mold in use or the slug to be cast therefrom. It sometimes happens, however, through carelessness or inexperience, that the operator fails 35 to make these adjustments, which failure often leads to disastrous results. For instance, if the ejector blade is too wide to enter the mold, serious damage is bound to occur, and the same is true if the distance 40 between the clamping jaws is less than the length of the composed line; or if the distance between the jaws is greater than the length of the line, a bad "squirt" is apt to result.

45 It is the object of my invention to obviate the foregoing objections, and to that end, I have provided mechanism which insures the corresponding adjustments of the line clamping and slug ejecting devices. More 50 specifically, I have connected both of these mechanisms to a common adjusting means, so that the adjustment of one effects the corresponding adjustment of the other. In

this way, the dangers before alluded to are not only avoided; but the adjustments of 55 the several parts are carried out simultaneously or at one operation, thus greatly facilitating and expediting the manipulation of the parts. The particular manner in which these advantages are obtained will be 60 fully pointed out in the detailed description to follow.

In the accompanying drawings, I have shown my invention as applied merely by way of example and in preferred form, and 65 obviously many changes and variations may be made therein which will still be comprised within its spirit. I therefore desire it to be understood that I do not limit myself to any specific form or embodiment, except in so far as such limitations are specified in the claims.

Referring to the drawings:

Figure 1 is a front perspective view of detached portions of a linotype machine with 75 my invention applied thereto;

Fig. 2 is a vertical section through a portion of the jaw adjusting devices;

Fig. 3 is a side elevation, partly in section, showing the connections between the 80 line clamping and slug ejecting mechanisms;

Fig. 4 is a section on the line 4-4 of Fig. 3;

Fig. 5 is a similar view showing the parts in different relative positions, and 85

Fig. 6 is a section on the line 6-6 of Fig. 5.

There are two general methods followed for casting type bars or slugs of different lengths, one involving the employment of a 90 so-called adjustable mold, *i. e.*, one whose mold slot may be shortened or lengthened to the required extent, and the other involving the use of a plurality of interchangeable molds having casting slots of the different 95 lengths desired. In the present instance, this latter method has been adopted for purposes of illustration. The several molds, only one of which is shown, marked B, are carried by the disk B¹ (see Fig. 3) which 100 is rotatably mounted upon the mold slide B² so as to present the selected mold first in a horizontal position to coöperate with an assembled line of matrices, and thereafter to carry the mold around to a vertical position, as indicated, to locate it in front of 105

the ejector mechanism which expels the slug therefrom.

During the casting operation, the composed line of matrices is supported before the mold between the clamping jaws C and D suitably sustained in the vise frame A. The left hand jaw D is mounted as usual to slide horizontally in a guideway in the vise frame so that the distance between it and the opposing jaw C may be varied according to the length of line employed. The position of the jaw D is determined by the adjustable straight-toothed rod E slidably supported in the vise frame and passing through a nut or block (shown by dotted lines in Fig. 1) which is adapted to be shifted laterally to a slight extent under the influence of the justifying devices in the ordinary way. The rod E is connected to the nut by the locking bolt or latch G mounted thereon and formed with teeth to engage those of the rod. In effecting the adjustment of the jaw D, the locking bolt G is first raised to disengage it from the rod E, and the latter is then moved endwise in one direction or the other as required. For this purpose, the rod is provided at its outer end with the arm E² to which is connected the bar or member E³ extending toward the right across the top of the vise frame A and connected to the operating devices later to be described. Before and after the rod is thus moved, the locking bolt G is moved to its inactive and active positions, respectively, these operations being carried out by means of the pivoted spring-actuated lever H and the underlying bar I. The bar I is seated upon and carried by the bar E³, the latter being provided with a series of buttons or protuberances (not shown) which normally engage in recesses or depressions formed in the under face of the bar I, so that when the bar I is moved longitudinally with respect to the bar E³, it will also be shifted or cammed laterally to rock the lever H upwardly and disengage the connected bolt G from the rod E. The spring I³ connected at one end to the bar E³ and at its opposite end to the bar I serves to restore the latter to its original position on the former and thus to allow the bolt G to be reengaged with the rod E. The foregoing parts and their mode of operation are fully set forth in the Kennedy U. S. Letters Patent No. 1,139,980, dated May 18, 1915, to which reference may be had for further particulars, if desired.

The slug ejecting mechanism herein illustrated is of the kind represented in the U. S. Letters Patent to John R. Rogers, No. 967,796, dated August 28, 1910, comprising the series of parallel blades or sections F¹ arranged one above another and guided between the vertical face of the mold slide B² on one side and the fixed vertical plate F³ on the opposite side. The several sections are free to move forward and backward inde-

pendently, and also so that any desired number may be brought into action conjointly to form an ejector of a width corresponding to the length of the slug to be cast, while the other sections remain inactive in their backward position. These ejector sections are actuated by the corresponding members F², mounted in grooves of the mold slide B² and adapted to be coupled to the main actuating slide F through the medium of the vertically adjustable bar F⁴, which has its lower end arranged to travel forward and backward on the rod F⁵ attached to the vertical slide F⁶. The slide F⁶ is adapted to be raised and lowered to select any desired number of the ejector blades for use, or to effect their operative connection with the main actuating slide F.

The foregoing parts taken from the two patents mentioned have been selected merely by way of example and to illustrate a preferred embodiment of my invention, such parts being in practical and commercial use today. It should be understood, however, that my invention may be adapted to other constructions which might require a totally different form of mechanism from that herein illustrated. My invention is directed broadly to any suitable means which will insure the corresponding adjustments of the line clamping and slug ejecting mechanisms. In the present instance, such means comprise a common adjusting device connected to both mechanisms, so that their adjustments may be carried out simultaneously and to corresponding extents.

In the particular embodiment illustrated, the common adjusting device is in the form of an operating hand-lever M² pivotally mounted at its rear end upon a transverse stud M³ fixed in the framework. Also pivotally mounted upon the stud M³ is a further lever O connected at its rear end to the vertical slide F⁶ controlling the adjustment of the ejector mechanism. These two levers are normally connected together in advance of their pivot by means of a locking pin P, which may however, be operated to disconnect them when desired, as will later be described. The connections between the operating lever M² and the jaw adjusting means comprise a pair of vertical rods or links L¹ and M¹, the latter being pivoted at its lower end directly to the operating lever, and the former to a hand plate L² also pivoted thereon, as at L³, and formed with a locking tooth L⁴ adapted to engage teeth on a stationary sector L⁵ and thus to hold the parts in their operated position. The locking engagement of the tooth L⁴ is maintained by a spring L⁶ interposed between the lever M² and the plate L².

At their upper ends, the rods L¹ and M¹ are connected to vertically movable racks L and M, respectively, meshing with pinions

J^3 and K^3 . The latter pinion is fixed to a fore-and-aft stub shaft K^2 suitably journaled in the vise frame A, and provided at its forward end with a bevel gear K engaging with rack teeth E^7 formed, for that purpose, on the extreme end of the jaw adjusting rod E⁸. The pinion J^3 is fast to a sleeve J^2 loosely surrounding the shaft K^2 and provided at its forward end with a similar bevel gear J meshing with rack teeth I^4 formed on the bar I, which controls the jaw locking means.

In effecting the adjustments of the parts, the operator grasps the lever M^2 , pressing in the hand plate L^2 to disengage its tooth L^4 from the sector L^5 . This relative movement of the hand plate shifts the connected rack L upwardly, effecting the independent rotation of the sleeve J^2 , which consequently moves the bar I longitudinally to the right to disengage the locking bolt G from the jaw adjusting rod E. The operating lever M^2 is then moved upwardly or downwardly as required, carrying with it both of the racks L and M, and causing the rotation of their respective bevel gears J and K, which thus shift the rods I and E³ conjointly to the left or right according to the direction of movement of the operating lever to set the jaw D in the desired position. This movement of the hand lever M^2 is also communicated to the operating lever O for the ejector adjusting slide F⁶, which is accordingly moved upwardly or downwardly as the case may be to select the requisite number of the individual ejector blades F¹ or to control their connection with the actuating slide F. After the parts have been adjusted in the above manner, the operator releases his hold upon the operating lever, and the connected plane L^2 is then pushed away by its spring L⁶ to restore the engagement of its locking tooth L^4 with the sector L^5 and thus to hold the parts in their operated position. The locking movement of the plate L^2 also restores, through the connections described, the reengagement of the locking bolt G with the toothed rod E, which holds the jaw D in its adjusted position. In short, when the distance between the clamping jaws C and D is varied, the width of the ejector blade is altered to correspond, these adjustments being effected simultaneously and by means of a common operating device.

It is sometimes desirable to cast short lines on long bodies, or the like, in which event it is necessary to set the clamping jaws at a distance apart less than the length of the mold slot, and it may be desired to do this without disturbing the width of the ejector blade. For this reason, I have provided means whereby the operating lever M^2 may be disconnected from the ejector adjusting slide F⁶ at will, so that the lever may be operated to effect the independent adjust-

ment of the line clamping jaws. In the present instance, such means comprise the locking pin P before referred to, which passes transversely through holes or apertures in the levers M² and O. The aperture 70 in the lever M² is open from below so as to permit it to straddle the locking pin or to be disengaged therefrom, but near its inner face the lever is formed with a pair of inwardly projecting lips M⁴ partly closing the aperture and adapted to embrace a fixed collar P¹ on the locking pin. Normally, the collar P¹ is held within the lips M⁴ by a spring P⁵, as in Fig. 4, but when the pin is drawn to the right against the action of the spring, 80 the collar is shifted out of engagement with the lips and passes into the enlarged and unobstructed portion of the aperture, as in Fig. 5, in which position of the parts the lever may clear the pin and be free to be 85 moved upwardly independently of the lever O (see Fig. 6). The locking pin is held in the latter or inactive position by means of a cam shaped piece P³ fixed thereon and arranged to coöperate with a beveled sector 90 plate N fixed to the pivot stud M³, the sector plate being of sufficient circumferential extent to allow the disconnection of the parts in various adjusted positions. The engagement of the piece P³ with the plate N also 95 serves to maintain the ejector adjusting slide F⁶ in its set position during the independent operation of the lever M². The locking pin P is provided with a handle P² to facilitate its manipulation.

As previously stated, I have shown my invention merely in preferred form and by way of example and as applied to a specific style of mechanism, but obviously many modifications and alterations therein, and in 105 its mode of adaptation, will suggest themselves to those skilled in the art without departure from its scope.

Having thus described my invention, its construction and mode of operation, what I 110 claim and desire to secure by Letters Patent of the United States, is as follows:

1. In a typographical casting machine, the combination of adjustable line clamping mechanism, adjustable slug ejecting mechanism, and interdependent means coöperating to insure the corresponding adjustments of the two mechanisms.

2. In a typographical casting machine, the combination of adjustable line clamping 120 mechanism, adjustable slug ejecting mechanism, and connections therebetween whereby the adjustment of one effects the corresponding adjustment of the other.

3. In a typographical casting machine, the combination of adjustable line clamping mechanism, adjustable slug ejecting mechanism, and a common adjusting device connected to both said mechanisms.

4. In a typographical casting machine, the 130

combination of a pair of line clamping jaws relatively adjustable to vary the distance between them, an ejector blade variable in width, and interdependent means co-operating to insure the corresponding adjustment of said parts.

5. In a typographical casting machine, the combination of a pair of line clamping jaws relatively adjustable to vary the distance between them, an ejector blade variable in width, and connections between said parts whereby the adjustment of the clamping jaws effects a corresponding change in the width of the ejector blade, or vice versa.

10. 6. In a typographical casting machine, the combination of a pair of line clamping jaws, adjusting means for setting the jaws at different distances apart, an ejector blade variable in width, adjusting means to alter 20 the width of the ejector blade to correspond to the adjustment of the jaws, and a common operating device for both said adjusting means.

15. 7. In a typographical casting machine, the combination of a pair of line clamping jaws, adjusting means for setting the jaws at different distances apart, a slug ejecting mechanism comprising a series of separate ejector blades and an actuating slide therefor, adjusting means for connecting any selected number of ejector blades to the actuating slide, and connections between the two adjusting means to insure the corresponding adjustment of the parts.

25. 8. In a typographical casting machine, the combination of a pair of line clamping jaws, adjusting means for setting the jaws at different distances apart, a slug ejecting mechanism comprising a series of separate 30 ejector blades and an actuating slide therefor, adjusting means for connecting any selected number of ejector blades to the actuating slide, and a common operating device for both said adjusting means.

35. 9. In a typographical casting machine, the combination of a pair of line clamping jaws, adjusting means for varying the distance between them, adjustable slug ejecting mechanism, means for adjusting said 40 mechanism to provide an ejector blade corresponding in width to the adjustment of the jaws, and connections between the two adjusting means to insure the corresponding adjustments of the parts.

45. 10. In a typographical casting machine, the combination of a pair of line clamping jaws, adjusting means for varying the distance between them, adjustable slug ejecting mechanism, means for adjusting said 50 mechanism to provide an ejector blade corresponding in width to the adjustment of the jaws, and a common operating device for said adjusting means.

55. 11. In a typographical casting machine, the combination of adjustable line clamping

mechanism, adjustable slug ejecting mechanism, and a common operating device for effecting the adjustments of said mechanisms conjointly or independently, as desired.

70

12. In a typographical casting machine, the combination of adjustable line clamping mechanism, adjustable slug ejecting mechanism, and connections therebetween whereby the adjustment of one effects the corresponding adjustment of the other, the said connections adapted to be broken at will to permit the adjustment of one of said mechanisms independently of the other.

75

13. In a typographical casting machine, the combination of a pair of line clamping jaws relatively adjustable to vary the distance between them, an ejector blade variable in width, and connections between said parts whereby the adjustment of the clamping jaws effects a corresponding change in the width of the ejector blade, or vice versa, the said connections adapted to be broken at will to permit the adjustment of one of said parts independently of the other.

80

14. In a typographical casting machine, the combination of a pair of line clamping jaws, adjusting means for setting the jaws at different distances apart, slug ejecting mechanism comprising a series of separate 95 ejector blades and an actuating slide therefor, adjusting means for connecting any selected number of ejector blades to the actuating slide, and connections between the two adjusting means to insure the corresponding 100 adjustments of the parts, the said connections adapted to be broken at will to permit the operation of one of the adjusting means independently of the other.

100

15. In a typographical casting machine, the combination of adjustable line clamping mechanism, adjustable slug ejecting mechanism, a common adjusting device connected to both said mechanisms, and means whereby the adjusting device may be disconnected 110 from one of said mechanisms to permit the independent adjustment of the other.

105

16. In a typographical casting machine, the combination of adjustable slug ejecting mechanism, means for effecting the adjustment of said mechanism, a pair of line clamping jaws, means for setting the jaws in different relative positions, means for locking and unlocking said jaws in such positions, and common operating devices for 115 all of said means.

115

17. In a typographical casting machine, the combination of adjustable line clamping mechanism, adjustable slug ejecting mechanism, a common adjusting device connected 125 to both said mechanisms, and locking means for holding the adjusting device in its operated position.

125

18. In a typographical casting machine, the combination of adjustable line clamping

130

mechanism, adjustable slug ejecting mechanism, a common adjusting device connected to both said mechanisms, means whereby the adjusting device may be disconnected from one of said mechanisms to permit the independent adjustment of the other, and means for maintaining the adjustment of

the disconnected mechanism during the independent adjustment of the other mechanism. ¹⁰

In testimony whereof, I have affixed my signature.

GEORGE P. KINGSBURY.
